BACKGROUND OF THE INVENTION

This invention relates to further development of two stroke internal combustion engines (from hereinafter referred to as 'TSICE'), which have one or more power cylinders with intake and exhaust ports, and a source of scavenging of the power cylinders.

Some terms and abbreviations used in the following description of previous art and present invention are defined below.

Pistons of TSICE move reciprocally within two limits, conventionally named as 'top dead center' and 'bottom dead center'. From hereinafter top dead center is referred to as 'TDC' and bottom dead center as 'BDC'.

Cavity of a cylinder, which is a space within the walls of the cylinder limited by a face of a piston, from hereinafter is referred to as 'cavity'.

In a double-sided cylinder, a piston has two faces, front and rear, which form two cavities within the walls of the cylinder on the opposite sides of the piston. In further description, due to the upright position of the cylinders on the drawings, the said cavities are referred to as 'upper cavity' and 'lower cavity'.

The main problems, known as deficiencies of TSICE, are the partial mixing of burned gases with the fresh air-fuel mixture, and the loss of some fresh air-fuel mixture through the exhaust ports at the time of scavenging.

As long as improvements can be achieved, reducing these problems, there is a chance to increase power per liter of displacement.

The so-called direct-flow scavenging/charging of the power cylinders has to be organized, when fresh air-fuel mixture fills up the cavity of the power cylinder starting from the intake port towards the exhaust port, so that burned gases always remain in the way of the air-fuel mixture to the exhaust port with minimum mixing.

One of the ways to achieve direct-flow scavenging/charging is to have two power cylinders, connected to each other with a common combustion chamber, where one of the cylinders has an intake port, and another has the exhaust port, as it is in RU Patent No. 2,063,524. Scavenging/charging starts in one cylinder and ends in the other, most importantly, cleaning the area of combustion chamber of burned gases and providing unidirectional displacement of burned gases with fresh air-fuel mixture.

TSICE, according to RU Patent No. 2,063,524, uses a pumping cylinder as a source of scavenging/charging of power cylinders. It comprises the first power cylinder with an intake port, connected to a pumping cylinder, and the second power cylinder with an exhaust port, said cylinders having a common combustion chamber and pistons connected each to its own crank, with the crank of the second piston having advanced crank angle against the crank of the first piston, enabling advanced opening and closing of the exhaust port in relation to the intake port.

Use of an additional cylinder, piston and crank solely for the purpose of scavenging/charging of another cylinder, increases the size and weight of the engine and reduces power per liter of displacement, and should be considered a drawback of the above named patent.

According to the totality of distinctive characteristics, the engine construction of RU Patent No. 2,063,524 is considered the closest prototype of present invention.

BRIEF SUMMARY OF THE INVENTION

Presented is TSICE, which has double-sided cylinders with upper and lower cavities used as power or pumping cavities, connected to each other in different combinations, which reduces the number of cranks and pistons and size and weight of the engine and increases power per liter of displacement.

BRIEF DESCRIPTION OF THE DRAWINGS

FIG. 1 shows one-cylinder TSICE at the end of the power stroke during scavenging/charging with piston having a baffle.

FIG. 2 shows cross section with a top view of the piston illustrating construction of the baffle, forming the gas flow.

FIG. 3 shows position of a piston at the moment of exhaust of burned gases from power cylinder before the beginning of scavenging, when the intake port is still closed.

FIG. 4 shows TSICE with pumping cylinder used for scavenging/charging of the power cylinder, with piston of the power cylinder having a baffle.

FIGS. 5 . . . 10 illustrate preferred embodiments of the present invention and their crank diagrams.

FIGS. 5A . . . 5D show the crank angle diagrams of TSICE with the crank of the first cylinder advanced by $\alpha^\circ = 180^\circ + \beta^\circ$ in relation to the crank of the second cylinder.

FIGS. 7A . . . 7D show the crank angle diagrams of TSICE with the crank of the first cylinder advanced by $\alpha^\circ = \beta^\circ$ in relation to the crank of the second cylinder.

FIG. 6 shows TSICE comprising two double-sided cylinders with two pumping and two power cavities and piston cranks having angular deviation β° against each other.

FIG. 8 shows TSICE comprising two double-sided cylinders, with four power cavities, connected to external supercharger, and piston cranks having angular deviation β° against each other.

FIGS. 9A . . . 9D show TSICE comprising two double-sided cylinders with two pumping and two power cavities and piston cranks having angular deviation $180^\circ + \beta^\circ$ against each other.

FIG. 9E shows four-cylinder TSICE, which is a combination of two engines, presented on FIGS. 9A . . . 9D.

FIGS. 10A . . . 10D show TSICE comprising two double-sided cylinders, with four power cavities, connected to external supercharger, and piston cranks having angular deviation $180^\circ + \beta^\circ$ against each other. 5

FIG. 11 shows TSICE comprising one power cylinder and one dual action cylinder, connected to a supercharger through a distribution valve. 10

FIG. 12 shows TSICE comprising two power cylinders and two dual action cylinders, connected to a supercharger through a distribution valve. 15

FIG. 13 shows single-row double-bank TSICE comprising power cylinder in the first bank and double-sided cylinder in the second bank with pumping cavity, connected to a supercharger. 15

FIG. 14 shows double-row double-bank TSICE comprising two power cylinders in the first bank and two double-sided cylinders in the second bank with pumping cavities, 20 connected to a supercharger, and piston cranks having angular deviation β° against each other.

FIGS. 15A, 15B show double-row double-bank TSICE comprising two power cylinders in the first bank and two double-sided cylinders in the second bank with pumping cavities, 25 connected to a supercharger, and piston cranks having angular deviation $180^\circ + \beta^\circ$ against each other.

FIGS. 16A, 16B show double-row double-bank TSICE comprising two pumping cylinders in the first bank, connected to a supercharger, and two double-sided cylinders in the second bank with piston cranks having angular deviation $180^\circ + \beta^\circ$ against each other. 30

FIG. 17 shows four-row double-bank TSICE comprising four power cylinders in the first bank and four double-sided cylinders in the second bank, whose all cavities are power cavities, connected to external supercharger. 35

FIG. 18 shows double-row double-bank TSICE comprising two power cylinders in the first bank and two double-sided cylinders in the second bank, whose upper cavities are 40 dual action cavities.

FIG. 19 shows TSICE comprising two power cylinders connected by a common combustion chamber and charged by two external superchargers. 45

FIG. 20 shows TSICE comprising two pairs of power cylinders, each pair having a common combustion chamber, and charged by two external superchargers. 50

One of the embodiments of the present invention, shown on FIG. 6, has two double-sided cylinders 1 and 2, whose upper cavities 17 and 19 are power cavities, and lower cavities 18 and 20 are pumping cavities. Cavities 17 and 19 have 5 common combustion chamber 66. Cavities 18 and 20 have common compression chamber 67. Power cavity 17 has the exhaust port 49, and power cavity 19 has the intake port 35. Pumping cavity 18 has the intake port 34, and pumping cavity 20 has the exhaust port 52, which is connected to the 10 intake port 35 by the channel 107. Crank 70 of the piston 9 has an advanced by β° crank angle against crank 71 of the piston 10, as shown in FIGS. 7A . . . 7D, enabling advanced opening and closing of the exhaust port 49 in relation to the intake port 35. Angle β° is an angle of rotation of crank 70, 15 corresponding to the piston 9 move from BDC to the piston, where piston 9 closes the exhaust port 49.

The method of operation of the TSICE on FIG. 6 is as follows.

At the end of the power stroke, when piston 9 of the power 20 cylinder is at BDC, as shown in FIG. 6, crank 71 still has β° to turn, before piston 10 will each BDC.

With piston 9 at BDC, the exhaust port 49 is completely open, allowing the escape of burned gases from cavities 17 and 19. Piston 10 still has not reached BDC and the intake 25 port 35 is still closed. When piston 9 moves up from BDC, and piston 10 still continues going down to its BDC, the exhaust port 49 starts closing simultaneously with opening of the intake port 35. At this time a direct-flow scavenging of power cavities takes place. A fresh portion of air-fuel mixture 30 entering through the intake port 35, fills consequently cavities 19 and 17, pushing out burned gases through the exhaust port 49. Compressed air-fuel mixture is delivered to the intake port 35 by the channel 107 from the pumping cavities 18 and 20. When the piston 10 reaches 35 BDC and opens completely the intake port 35, piston 9 completely closes the exhaust port 49, which represents the end of scavenging. The charging of the cavities 19 and 17 with fresh air-fuel mixture continues through the still open intake port 35, until it is completely closed by the piston 10, 40 moving up from BDC. After the closing of the port 35, the air-fuel mixture is compressed in power cavities 17 and 19. Pistons 9 and 10, move up, piston 9 reached TDC first, and when it starts going down and piston 10 reaches TDC, ignition of compressed air-fuel mixture happens, initiating a power stroke. While moving up, pistons 9 and 10 create a 45 vacuum in the pumping cavities 18 and 20. When the piston 9 reaches TDC, it opens the intake port 34, and the created vacuum induces suction of fresh-air fueled mixture into the pumping cavities 18 and 20. During the power stroke, 50 moving down, pistons 9 and 10 compress it, and at the end of power stroke, the process of scavenging/charging of the power cavities starts, as described above.

Another embodiment of the present invention, shown in FIG 8, has two double-sided cylinders 1 and 2, but unlike the 55 engine on FIG. 6, it has all cavities being power cavities, including upper cavities 17 and 19 and lower cavities 18 and 20. Each pair of cavities has its common combustion chamber 66 and the spark plug 79. Instead of pumping cavities used in engine on FIG. 6, an external source of scavenging 60 is used, like the supercharger 91, which can be driven by an electric motor or by the engine itself, or by the energy of exhaust gases (turbo-supercharger). The cavities 17 and 18 have exhaust ports 49 and 50, and the cavities 19 and 20 have intake ports 35 and 36. Air-fuel mixture from the 65 supercharger 91 is delivered with constant pressure to the intake ports 35 and 36. The crank 70 of the piston 9 has a crank angle advanced by β° against the crank 71 of the

DETAILED DESCRIPTION OF THE INVENTION

Present invention is applicable to the following three types of TSICE:

- 1) spark ignited (e.g. gasoline, propane) engine with an external mixing of air and fuel in the intake manifold and use of air-fuel mixture for scavenging of power cylinders;
- 2) spark ignited (e.g. gasoline) engine with scavenging of power cylinders with pure air and direct fuel injection into the power cylinders at the beginning of compression stroke after their ports are already closed;
- 3) self-ignited (diesel) engine with scavenging of power cylinders with pure air and direct fuel injection into the power cylinders at the end of compression stroke.

All three types of engines have an oil-filled crankcase. TSICE charged with air-fuel-oil mixture through a dry crankcase are not considered, since they are pollutive and have other known disadvantages.

If exhaust ports of the power cylinders close before their intake ports, charging of power cylinders can continue after the exhaust ports are closed, making coefficient of admission possibly more than 1.0.

In TSICE of second and third types cylinders are scavenged/charged with pure air, having fuel injected directly into the cavity of power cylinder. In these engines low pressure fuel injector 101 in the engine intake manifold is not present. Instead, in the second type of spark-ignited engine low pressure direct fuel injector 99 installed in the power cylinder is used together with a spark plug 79. In self-ignited TSICE of the third type spark plug 79 is replaced with a high pressure direct fuel injector 80. The direct injection of fuel into the power cylinders after scavenging is complete and ports of the power cylinders are closed, eliminates fuel loss and mixing of a fresh charge with burned gases.

Drawings and descriptions are made as for the first type of TSICE.

piston **10**, as shown on FIG. 7, enabling advanced opening and closing of the exhaust port **49** in relation to the intake port **35** and the exhaust port **50** in relation to the intake port **36**.

The method of operation of the TSICE on FIG. 8 is as follows.

At the end of the power stroke, when piston **9** of the power cylinder is at BDC, as shown on FIG. 8, the crank **71** still has β° to turn, before the piston **10** will reach BDC.

With piston **9** at BDC exhaust port **49** is completely open allowing the escape of burned gases from cavities **17** and **19**. Piston **10** still has not reached BDC and the intake port **35** is still closed. When piston **9** moves up from BDC, and piston **10** still continues going down to BDC, the exhaust port **49** starts closing simultaneously with opening of the intake port **35**, which initiates a direct-flow scavenging of cavities **19** and **17** with pressurized air-fuel mixture from the supercharger. The scavenging continues until the exhaust port **49** is closed. At that moment, the piston **10** reaches BDC, and the intake port **35** remains open until completely closed by piston **10**, moving up from BDC. This allows the supercharger to create excessive pressure of air-fuel mixture inside the cavities **19** and **17**. During the compression stroke the pistons **9** and **10** reach TDC one before another. When piston **10** reaches TDC, the compressed air-fuel mixture is ignited by a spark plug and a power stroke starts. The pistons **9** and **10** go down and after the piston **9** reaches BDC a new cycle begins. Operation of power cavities **18** and **20** goes exactly the same way, as of cavities **17** and **19**, described above, but with the opposite timing. That doubles the amount of power, generated by the TSICE, compared with the TSICE on FIG. 6. Additional increase of power per liter of displacement is achieved by the use of a supercharger, which makes the coefficient of admission of the power cylinders more than 1.0.

TSICE shown on FIGS. 9A . . . 9D is the third embodiment of the present invention with double-sided cylinders **1** and **2**, where pistons **9** and **10**, reciprocally movable therein, are connected to cranks **70** and **71**. The crank **70** has a crank angle, advanced against crank **71** by $\alpha^\circ=180^\circ+\beta^\circ$, as shown on FIGS. 5A . . . 5D, where β° is an angle of rotation of the crank **70**, corresponding to the piston **9** move from TDC down to the position when piston **9** closes the exhaust port **50**. The cavities **18** and **19** are power cavities, connected to each other by channel **106**, shown on FIGS. 9C, 9D. The channel **106** represents the common combustion chamber for cavities **18** and **19**, which have the common spark plug **79**, common intake ports **35**, located in cavity **19**, and common exhaust port **50**, located in cavity **18**. Cavities **17** and **20** are pumping cavities. They have individual intake ports **33** and **36** and exhaust ports **49** and **52**, connected to the intake ports **35** by channels **102** and **107**.

The method of operation of the TSICE on FIGS. 9A . . . 9D is as follows.

At the end of a compression stroke, as shown on FIGS. 9A and 9B, air-fuel mixture is compressed in the power cavities **18** and **19** and a vacuum is created in the pumping cavities **17** and **20**. When the piston **9** of the power cylinder is at BDC (FIG. 9A), the intake port **33** opens and vacuum inside the pumping cavity **17** draws in a fresh portion of air-fuel mixture. The crank **71** still has β° to turn, before piston **10** will reach TDC. When that happens (FIG. 9B), the intake port **36** opens and vacuum inside the pumping cavity **20** draws in a fresh portion of air-fuel mixture. At the same time, air-fuel mixture, compressed in power cavities **18** and **19** is ignited with the spark plug **79**, and a power stroke begins with simultaneous compression of a new portion of

air-fuel mixture in the pumping cavities **17** and **20**. When piston **9**, on its way up, reaches TDC (FIG. 9C) the exhaust port **50** opens, allowing the release of the burned gases from the power cavities. Since then, both pistons move down: the piston **9**, closing the exhaust port **50**, and the piston **10**, opening the intake ports **35** of power cylinders. Until the exhaust port **50** closes, the direct-flow scavenging/charging of the power cavities **19** and **18** goes on. Compressed in the pumping cavities **17** and **20**, an air-fuel mixture is released through the channels **102** and **107** into the cavity **19** and from there through the channel **106** into the cavity **18**, pushing the rest of the burned gases out of the exhaust port **50**. The process of scavenging ends when the piston **10** reaches BDC and the piston **9** closes the exhaust port **50** (FIG. 9D). The intake ports **35** remain open and process of charging of the power cylinders continues until piston **10**, moving up from BDC, closes ports **35**, and another compression stroke starts.

An advantage of this version of TSICE is that the phase opposition of the cranks **70** and **71** balances the forces applied to the crankshaft bearings and inertial masses of the engine.

In practical applications for smoother performance this type of engine will include four double-sided cylinders, combined in pairs, as shown on FIG. 9E.

TSICE according to the present invention, shown on FIGS. 10A . . . 10D, unlike the previous embodiment, has all four cavities of two double-sided cylinders being power cavities. The power cavities **18** and **19** are connected by the channel **106**, as shown on FIGS. 10C, 10D. The power cavities **17** and **20** are connected by the channel **108**, as shown on FIGS. 10A, 10B. Each pair of cavities has its own spark plug **79**. The cavities **18** and **19** have the common intake port **35** and exhaust port **50**. The cavities **17** and **20** have the common intake port **36** and the exhaust port **49**. The crank **70** has a crank angle, advanced against the crank **71** by $\alpha^\circ=180^\circ+\beta^\circ$, as shown on FIGS. 5A . . . 5D, where β° is an angle of rotation of the crank **70**, corresponding to the piston **9** move from BDC up to the position when the piston **9** closes the exhaust port **49**. Since cylinders of this TSICE do not have pumping cavities, the external supercharger **91**, connected by the intake manifold **92** to the intake ports, is used for scavenging/charging of the power cavities.

The method of operation of the TSICE on FIGS. 10A . . . 10D is as follows.

When the piston **9** reaches BDC at the end of power stroke, as shown on FIG. 10A, the exhaust port **49** opens, allowing the escape of burned gases from the cavities **17** and **20**. During another β° of crankshaft rotation, both pistons move up: the piston **9** moves from BDC, closing the exhaust port **49**, and the piston **10** moves towards TDC, opening the intake port **36**. Until the exhaust port **49** is completely closed, the direct-flow scavenging/charging of the cavities **20** and **17** takes place. Pressurized air-fuel mixture from the supercharger **91** fills the cavities **20** and **17** through the intake port **36** and the channel **108**, pushing the rest of the burned gases out of the exhaust port **49**. The process of scavenging ends, when the piston **10** reaches TDC and the piston **9** closes the exhaust port **49** (FIG. 10B). The intake port **36** remains open and the process of charging of the power cylinders continues until the piston **10**, moving down from TDC, closes the port **36** and a compression stroke begins in the cavities **17** and **20**. At the time of scavenging/charging of the cavities **17** and **20**, another pair of cavities, **18** and **19**, is at the end of a compression stroke. When the piston **10** reaches TDC, the compressed air-fuel mixture in the cavities **18** and **19** is ignited, initiating in them a power

stroke. This gas combustion causes the pistons **9** and **10** to move towards each other, piston **9** to TDC and piston **10** to BDC, compressing a new portion of air-fuel mixture in the cavities **17** and **20**. When the piston **9** reaches TDC (FIG. 10C), the exhaust port **50** opens, allowing the release of the burned gases from the power cavities **18** and **19** through the channel **106** at the end of a combustion stroke. During another β° of crankshaft rotation, both pistons move down: the piston **9** moves from TDC, closing the exhaust port **50**, and piston **10** moves towards BDC, opening the intake port **35**. Until the exhaust port **50** is completely closed, the direct-flow scavenging/charging of the cavities **18** and **19** takes place. Pressurized air-fuel mixture from the supercharger **91** fills cavities **18** and **19** through the intake port **35** and channel **106**, pushing the rest of the burned gases out of the exhaust port **50**. The process of scavenging ends, when the piston **10** reaches BDC and the piston **9** closes the exhaust port **50** (FIG. 10D). The intake port **35** remains open and the process of charging of the power cylinders continues until the piston **10**, moving up from BDC, closes the port **35** and a compression stroke begins in the cavities **18** and **19**. At the time of scavenging/charging of the cavities **18** and **19**, another pair of cavities, **17** and **20**, is at the end of a compression stroke. When the piston **10** reaches BDC, a compressed air/fuel mixture in the cavities **17** and **20** is ignited, initiating in them a power stroke. This gas combustion causes the pistons **9** and **10** to move towards each other, the piston **9** to BDC and the piston **10** to TDC, compressing a new portion of air-fuel mixture in the cavities **18** and **19**. When the piston **9** reaches BDC (FIG. 10A), the process continues, as described above.

All the engines, described above, achieve the object of increasing of power per liter of displacement.

The few shown examples illustrate, how wide can be the variety of applications of present invention, from small appliances, to the huge diesel marine engines.

Many more modifications of the present invention are possible, and among those, described above, TSICE, presented on FIG. 10, is considered as the preferred embodiment. Nevertheless, other shown embodiments may be given preference in different applications.

The scope of the invention should be determined by the appended claim, rather than by the examples given.

We claim:

1. A two stroke internal combustion engine comprising first power cylinder with a first piston reciprocally movable therein and an intake ports and second power cylinder with a second piston reciprocally movable therein and an exhaust ports, said pistons being connected each to its own crank, with the crank of the second piston having advanced crank angle against the crank of the first piston, enabling advanced opening and closing of the exhaust port in relation to the intake port, said cylinders being double-sided, with upper power cavities and lower power cavities on the opposite sides of the pistons, said cavities interconnected by passages in pairs, with lower power cavities separated from cranks by a transverse partition, and the intake ports of power cavities of the first cylinder connected to a source of scavenging and supercharging, with improvements, including said crank of the second piston having additional advancement of 180° against the crank of the first piston, providing movement of said pistons in opposition to each other, and said passages interconnecting lower power cavity of the first cylinder with upper power cavity of the second cylinder and upper power cavity of the first cylinder with lower power cavity of the second cylinder.
